UNITED STATES PATENT OFFICE.

AUGUST BECKER, OF NEW YORK, N. Y.

MIRROR-SUPPORT.

SPECIFICATION forming part of Letters Patent No. 651,129, dated June 5, 1900.

Application filed September 21, 1899. Serial No. 731,151. (Model.)

To all whom it may concern:

Be it known that I, AUGUST BECKER, a citizen of the United States, residing at New York, borough of Manhattan and State of New York, 5 have invented certain new and useful Improvements in Mirror-Supports, of which the following is a specification.

This invention relates to an improved mirror-support that can be used as an ordinary 10 hand-mirror and stand or as a wall-mirror for shaving and other purposes; and the invention consists of a mirror-support comprising certain features of construction and combinations of parts to be hereinafter described and 15 then claimed.

In the accompanying drawings, Figure 1 represents a perspective view of my improved mirror-support, showing the same in position as a stand. Fig. 2 is a perspective view showing 20 the mirror suspended on a wall. Fig. 3 is a horizontal section on line 3 3, Fig. 1, drawn on a larger scale; and Fig. 4 is a horizontal section on line 4 4, Fig. 2, likewise drawn on a larger scale.

25 Similar letters of reference indicate corresponding parts.

Referring to the drawings, A represents a mirror-plate which is provided with a backing B of pasteboard, wood, or other suitable 30 material. The mirror-plate may either be a plain rectangular piece of looking-glass or a beveled plate, as desired.

C is the supporting-frame, which is made of a single piece of wire of suitable thickness, 35 said wire being bent into proper shape, the parallel main portion or arms d being bent inwardly at their upper ends and either sprung into metallic clasps D, that are attached to the sides of the mirror-plate A, or sprung into 40 suitable sockets in the back of the mirror-plate, provided that said back is made of a layer of wood or other substance of sufficient thickness, as shown in Figs. 2 and 4. The clasps D are preferably made of sheet-brass 45 or other suitable metal and tightly fitted to the front and back of the mirror-plate, being provided with a hole or depression for the inwardly-bent ends of the supporting-frame C, so as to form a pivotal connection between 50 the frame and mirror-plate. The lower opposite ends of the parallel arms d are bent in-

wardly at a suitable angle to the arms d, so as to form short approximately alined inwardly-extending portions d', from which extends in backward direction a V-shaped portion or stay d², which forms either the supporting portion of the wire frame, as shown in Fig. 1, when the same is placed on a bureau or other suitable piece of furniture, or which forms the hanger by which the mirror is suspended from a nail on the wall, as shown in Fig. 2. The V-shaped stay d² may also be used as a handle when the mirror is used as a hand-mirror. The alined disposition of the portions d' furnishes a broad base for the 65 mirror when the device is used as a stand and a rest for the same when the device is hung up, which prevents the wabbling or tipping over of the mirror.

My improved mirror-support has the advantage that by means of a very simple attachment of bent wire the mirror can be used as a hand-mirror or as a mirror-stand on a piece of furniture or that it can be suspended from the wall, so as to be used for shaving 70 or other purposes. The attachment can be manufactured at small expense, especially when the wire frame is bent by means of suitable dies, while when a cheap mirror-plate is used in connection with the frame an 75 inexpensive, yet very convenient and useful, mirror is obtained. The supporting-frame can be used for supporting photographs or other pictures, advertising novelties, &c., in place of a mirror, in which case a plain or 80 beveled glass plate may be used for covering the pictures, the attachment of the supporting-frame to the glass plate being made in the same manner as for the mirror-plates.

Having thus described my invention, I 90 claim as new and desire to secure by Letters Patent—

1. The combination, with a mirror-plate, of clasps applied over the side edges of the mirror-plate, a supporting-frame pivoted to 95 said clasps and composed of arms having inwardly-bent ends, inwardly-bent portions at the other ends of said arms, and a stay extending backwardly from said inwardly-bent portions, substantially as set forth.

2. The combination, with a mirror-plate, of a spring-metal supporting-frame provided

with arms within which the mirror-plate is arranged, and clasps at opposite sides of said frame, engaging and clasping opposite sides of the mirror-plate, substantially as set forth.

5 3. The combination, with a mirror-plate, of a spring-metal supporting-frame, and clasps pivoted to opposite sides of said frame and adapted to engage over and clasp the opposite edges of the mirror-plate, whereby a
10 pivotal connection between the mirror-plate

and frame is provided, substantially as set forth.

In testimony that I claim the foregoing as my invention I have signed my name in presence of two subscribing witnesses.

AUGUST BECKER.
